United States Patent Office

Des. 229,442
Patented Nov. 27, 1973

229,442

PHONOGRAPH CONSOLE

James E. Mohn, Syracuse, N.Y., assignor to
General Electric Company

Filed Sept. 27, 1971, Ser. No. 184,327

Term of patent 14 years

Int. Cl. D14—01

U.S. Cl. D56—4 R

FIG.1

FIG.2

FIG.3

FIG. 1 is a front elevational view of a phonograph console, showing my new design;

FIG. 2 is a side elevational view, the opposite side being substantially a mirror image thereof;

FIG. 3 is a top plan view;

FIG. 4 is a perspective view; and

FIG. 5 is an exploded view thereof with the loudspeakers removed and the sliding shelf partly pulled out.

I claim:

The ornamental design for a phonograph console, as shown and described.
